DESIGN FOR A COVER FOR A COMBINED WASHING MACHINE AND WRINGER

Carl R. Wolff, Chicago, Ill.

Application October 30, 1939, Serial No. 87,927

Term of patent 14 years

To all whom it may concern:

Be it known that I, Carl R. Wolff, a citizen of the United States, residing at 3626 Lexington Street, Chicago, in the county of Cook and State of Illinois, have invented a new, original, and ornamental Design for a Cover for a Combined Washing Machine and Wringer, of which the following is a specification, reference being had to the accompanying drawing, forming part thereof.

Fig. 1 is a perspective view of a cover for a combined washing machine and wringer, showing my new design.

Fig. 2 is a front elevational view thereof.

Fig. 3 is a side view thereof.

Fig. 4 is a top plan view thereof.

The characteristic features of my design comprise a cover for a combined washing machine and wringer composed of and formed of individual panels of the specific configurations and associated in the manner shown.

I claim:

The ornamental design for a cover for a combined washing machine and wringer, substantially as shown and described.

CARL R. WOLFF.
